UNITED STATES PATENT OFFICE.

ARTHUR L. WAUGH, OF CAMBRIDGE, MASSACHUSETTS.

STEERING-GEAR FOR VEHICLES.

SPECIFICATION forming part of Letters Patent No. 743,357, dated November 3, 1903.

Application filed February 9, 1903. Serial No. 142,455. (No model.)

To all whom it may concern:

Be it known that I, ARTHUR L. WAUGH, a citizen of the United States, residing at Cambridge, in the county of Middlesex and State 5 of Massachusetts, have invented new and useful Improvements in Steering-Gear for Vehicles, of which the following is a specification.

This invention relates to a steering-gear for horseless vehicles, the object of the invention 10 being to provide a strong, simple, and easily-operated mechanism by means of which the steering axle and wheels may be easily turned at different angles with relation to the body of the vehicle by the chauffeur, but which 15 will lock said steering axle and wheels in a fixed position with relation to the body of the vehicle against accidental displacement by reason of the wheels striking an obstruction or inequality upon the road over which the 20 vehicle is traveling.

The invention consists, in a device of the character described, of a casing, preferably in two parts, a steering-rod and a rotatory-screw, both journaled in said casing, bevel- 25 gears rotatably connecting said rod and screw, a nut having screw-threaded engagement with said screw, and specific means by which the nut is prevented from rotating.

The invention again consists in certain im- 30 proved adjusting means whereby wear or backlash between the parts is eliminated.

The invention finally consists in the com- 35 bination and arrangement of parts set forth in the following specification, and particularly pointed out in the claims thereof.

Referring to the drawings, Figure 1 is a central longitudinal section, partly in elevation, of my improved steering-gear. Fig. 2 is a transverse section taken on line 2-2 of Fig. 1 looking toward the left in said figure. Fig. 3 is a detail side and end elevation of one of the journal-bearing boxes. Fig. 4 is a section taken on line 4-4 of Fig. 1. Fig. 5 is a detail side and end elevation of another of 40 the journal-bearing boxes. Fig. 6 is a detail section taken on line 6-6 of Fig. 1. Fig. 7 is a diagrammatic view illustrating a modified arrangement of the bevel-gears with relation to the steering-rod. Fig. 8 is a diagrammatic 45 front view of the gears and rod illustrated in Fig. 7.

Like numerals refer to like parts throughout the several views of the drawings.

In the drawings, 10 is a casing formed in two parts 11 and 12, held firmly together by 55 bolts 9-9.

13 is the steering-rod, which extends upwardly at a suitable angle from the casing 10 and is provided at its upper end with a steering-wheel, (not shown in the drawings,) by 60 means of which it may be conveniently rotated.

The steering-rod 13 is journaled in a journal-box 14, which is rectangular in cross-section and is held firmly in position between 65 the two parts 11 and 12 of the casing 10. The journal-box 14 is provided at its upper end with a flange 15 and bears at its lower end against a collar 16, encircling the rod 13.

The steering-rod 13 is prevented from moving longitudinally in the box 14 by a collar 17, which bears against the flange 15 upon said journal-box, and by a bevel-gear 18, which bears against the collar 16. The bevel-gear 18 is held against a shoulder on the steering-rod 13 by a nut 19 and is prevented from 70 rotating thereon by a key 20.

The bevel-gear 18 meshes into another bevel-gear 21, fast to a rotary screw 22, which is journaled to rotate in boxes 23-42, said boxes being 80 rectangular in cross-section and clamped between the two parts of the casing 10. Flanges 24 and 41 are provided upon the boxes 23 and 42, respectively, said flanges arranged to bear against the interior face of the casing 10. 85 Endwise movement of the screw 22 in the boxes 23 and 42 is prevented by collars 25-26, fast thereto, which bear against the flanges 24 and 41, respectively. A nut 27 has screw-threaded engagement with the screw 22 and 90 is prevented from rotating when said screw is rotated, as hereinafter described, by a feather 28, integral with said nut, extending longitudinally thereof, and arranged to slide in ways 29, provided between the two parts of said casing, said ways being formed by means of ribs 30-30, extending downwardly from the interior of the two parts 11 and 12. The nut 27 is provided upon its under side with a rack 31, which extends longitudinally of said nut 95 and meshes into a segmental spur-gear 32, fastened to a steering-shaft 33, journaled to 100

rock in rectangular boxes 34 43. The steering-shaft 33 has fastened thereto and preferably integral therewith a downwardly-projecting arm 35, which is connected by a link 5 48 to a steering-knuckle fast to the steering-axle of the vehicle. (Not shown, but well known to those skilled in this art.)

The boxes 34 43 are rectangular in cross-section and fit in recesses 36 36, provided in 10 the two parts 11 and 12 of the casing 10. Said boxes may be adjusted, together with the shaft 33 and spur-gear 32, toward and away from the rack 31 by means of adjusting-screws 37, said adjusting-screws bearing against the 15 under side of said boxes and having screw-threaded engagement with the two parts 11 and 12 of the casing. The adjusting-screws 37 are locked in position when the spur-gear has been adjusted to the proper height and 20 relation to the rack 31 by means of the set-nuts 38 38. The casing 10 is provided with flanges 39 39, which form a convenient means for attaching said casing to the frame of the vehicle and form a tight joint therebetween, 25 so that the space inclosed between said parts may be filled with oil, and the bevel-gears, screw, nut, rack, and segmental gear hereinbefore described may be thus run in a bath of oil and be practically free of friction, resulting 30 in a long life to the parts. It will be noted that the portion of the steering-shaft 33 which is journaled in the box 43 is of smaller diameter than that portion which is journaled in the box 34, Fig. 2; but the distance laterally 35 across the outside of the boxes 43 and 34 is the same, so that said boxes are interchangeable in the recesses 36 in the frame to receive said boxes. Hence the steering-arm 35 may be reversed and placed upon the right 40 side of the casing, Fig. 2, instead of upon the left, as therein shown.

As the steering-rod 13 is rotated there is more or less wear and friction between the collar 17 and the flange 15, and also between 45 the bevel-gear 18, collar 16, and the lower end of the box 14, and also between the teeth of the bevel-gears 18 and 21. In order to take up this wear, an adjusting-screw 44 is provided, which is tapped through the flange 15 50 and bears against an ear 45 upon the casing 10. When the adjusting-screw is turned in the proper direction, it forces the box 14 upwardly, Fig. 1, first taking up any wear between the flange 15 and collar 17 and then 55 pushing the steering-rod, together with the bevel-gear 18, upwardly until the backlash between the teeth of the bevel-gears 18 and 21 is taken up. In order to take up any wear between the collars 25 and 26 on the rotary 60 screw 22 and the boxes 23 and 42, in which said rotary screw rotates, adjusting-screws 46 46 are provided, Fig. 4. These adjusting-screws pass through ears 47 47 upon the journal-box 23 and have screw-threaded engagement 65 with the casing 10, so that by turning said screws in the proper direction the box 23 may be forced toward the right, Fig. 1, push-

ing the collar 25 and screw 22 toward the right, together with the collar 26, until said collar 26 comes in contact with the flange 41 upon 70 the box 42. It will thus be seen that substantially all of the running parts of my improved steering-gear may be readily adjusted from the exterior of the casing, rendering the device convenient and practical. 75

The general operation of the device hereinbefore specifically described is as follows: The steering-rod 13 is rotated by means of a handle attached thereto, thus rotating the bevel-gears 18 and 21 and the screw 22. As 80 the screw 22 is thus rotated the nut 27 is moved longitudinally of said screw, said nut being prevented from rotating by the feather 28, which slides longitudinally in the ways 29. As the nut 27 is thus moved longitudinally 85 of the screw 22 the rack 31 imparts a rotary motion to the spur-gear 32 and to the shaft 33, rocking the arm 35, and thus turning the steering axle and wheels at different angles through the link 36, connected thereto by a steering-knuckle. The vertical adjustment of the boxes 34, hereinbefore described, guards against any backlash or play 90 between the teeth upon the rack 31 and upon the gear 32, thus guarding against any accidental change in position of the steering-axle 95 with relation to the body of the vehicle.

It will be noted that the bevel-gear 18 is larger in diameter than the bevel-gear 21, so that by turning the steering-rod 13 through 100 a slight angle an increased rotary motion will be imparted to the screw 22 and to the shaft 33, and thus for a certain result in the changing of the angle of the steering-axle with relation to the body of the vehicle as compared 105 with a certain angle of rotation imparted to the steering-rod 13 the length of the steering-arm 35 may be made much shorter, and consequently much more rigid, than would be the case if the steering-wheel were applied 110 directly to the screw 22 or than would be the case if the gears 18 and 21 were of the same pitch-diameter.

In the form of my device illustrated in Figs. 1 to 4, inclusive, the arm 35 moves in a 115 vertical plane extending longitudinally of the vehicle; but in some cases it is desirable that said arm should move in a plane extending transversely of the vehicle and still that the steering-rod 13 should be maintained in the same position with relation to the vehicle that it occupies in the form illustrated in Figs. 1 to 4, inclusive. This result may be attained by placing the bevel-gears in the relation to each other shown in Figs. 120 7 and 8, in which the bevel-gear 18, fast to the steering-rod 13, meshes into a bevel-gear 40, fast to the rotary screw 22. It will also be noted that the steering-rod may be placed at different angles in a vertical plane extending 125 longitudinally of the median line of the screw 22, Figs. 1 to 4, inclusive, by changing the relative diameters of the bevel-gears 18 and 21. It will therefore be seen that the 130

advantages secured by connecting the steering-rod 13 to the rotary screw 22 by means of the bevel-gears are twofold, viz: the screw 22 may be rotated through a greater angle than that through which the steering-rod 13 is rotated by properly proportioning the pitch-diameters of said bevel-gears, and thus the length of the steering-arm 35 may be shortened and said arm rendered stronger and stiffer; also, the steering-rod 13 may be placed at different angles in a vertical plane extending longitudinally of the rotary screw 22, as hereinbefore set forth, and, further, the median line of the steering-rod 13 may be arranged in a vertical plane at right angles to the vertical plane in which the median line of the rotary screw 22 is located, as illustrated in Figs. 7 and 8, and by such arrangement the link 36 be given a motion transversely of the vehicle instead of longitudinally of said vehicle.

Having thus described my invention, what I claim, and desire by Letters Patent to secure, is—

25 1. In a steering-gear for vehicles, a casing in two parts, a rotary screw journaled in said casing, the longitudinal median plane of said screw coincident with the plane of division of said casing, ribs upon the interior of said casing parallel to and upon opposite sides, respectively, of said plane, a nut having screw-threaded engagement with said screw, and a feather upon said nut projecting therefrom between said ribs.

35 2. In a steering-gear for motor-vehicles, a casing in two parts, a steering-rod, a rotary screw, both journaled in said casing, the longitudinal median plane of said screw and steering-rod coincident with the plane of division of said casing, ribs upon the interior of said casing parallel to and upon opposite sides, respectively, of said plane, bevel-gears rotatably connecting said rod and screw, a nut having screw-threaded engagement with 45 said screw, and a feather upon said nut projecting therefrom between said ribs.

3. In a steering-gear for motor-vehicles, a casing in two parts, journal-bearing boxes clamped between said parts, a rotary screw 50 journaled in said boxes, the longitudinal median plane of said screw coincident with the plane of division of said casing, ribs upon the interior of said casing parallel to and upon opposite sides, respectively, of said plane, a nut having screw-threaded engagement with

said screw, and a feather upon said nut projecting therefrom between said ribs.

4. In a steering-gear for motor-vehicles, a casing in two parts, journal-bearing boxes clamped between said parts, flanges upon said 60 journal-boxes arranged to bear against the interior of said casing, a rotary screw journaled in said boxes, collars fast to said screw at opposite ends thereof and bearing, respectively, against one of said flanges, and means 65 to adjust one of said journal-boxes longitudinally of said screw from the exterior of said casing.

5. In a steering-gear for motor-vehicles, a casing in two parts, a steering-rod, a rotary 70 screw, bevel-gears rotatably connecting said rod and screw, a journal-box in which said rod is journaled, and means to adjust one of said bevel-gears with relation to the other from the exterior of said casing. 75

6. In a steering-gear for motor-vehicles, a casing in two parts, a steering-rod, a rotary screw, bevel-gears rotatably connecting said rod and screw, a journal-box in which said steering-rod is journaled, and means to adjust 80 said box and rod longitudinally thereof from the exterior of said casing for the purpose specified.

7. In a steering-gear, a casing in two parts, a steering-rod, a rotary screw, bevel-gears rotatably connecting said rod and screw, a journal-box in which said steering-rod is journaled, means to adjust one of said bevel-gears, with relation to the other, and an adjusting-screw having screw-threaded engagement 85 with said box, the end of said screw adapted to bear against said casing and forming a means for adjusting said box and rod longitudinally thereof from the exterior of said casing. 95

8. In a steering-gear, a casing in two parts, a rotary screw, a nut having screw-threaded engagement with said screw, means to prevent said nut from rotating, a journal-box in which said rotary screw is journaled, and means to adjust one of said boxes longitudinally of said screw from the exterior of said casing for the purpose specified. 100

In testimony whereof I have hereunto set my hand in presence of two subscribing witnesses. 105
